UNITED STATES PATENT OFFICE.

MAURY W. HIBBARD, OF CHICAGO, ILLINOIS, ASSIGNOR TO THE W. W. SPRAGUE COMPANY, OF SAME PLACE.

TRAMWAY-SWITCH.

SPECIFICATION forming part of Letters Patent No. 569,199, dated October 13, 1896.

Application filed July 22, 1895. Serial No. 556,711. (No model.)

To all whom it may concern:

Be it known that I, MAURY W. HIBBARD, of Chicago, Illinois, have invented certain new and useful Improvements in Tramway-
5 Switches, of which the following is a specification.

This invention relates to a switch for elevated-carrier systems, such as are commonly employed in slaughtering-houses. In systems
10 of this kind it is necessary to provide for numerous branch tracks, and at the junction of these latter with the main track there must be provided a switch of some kind, so that the carrier may be sent over the main track
15 or over the branch at will. My invention has to do with a switch of this character; and its object is to provide a switch of improved construction in which the main track and the switch have movable rail-sections arranged
20 at the junction and connected to a common crank-shaft in such manner that by the rocking thereof one of the movable rail-sections will be placed in position to close a gap in the track while the other is removed.

25 My invention also comprises an actuating-lever for moving such rail-sections, and which is adapted also to serve as a stop or lock to prevent carriers passing over the main track when the switch is in use.

30 In the accompanying drawings, Figure 1 is a plan view of the switch, showing the main line in condition for use, the dotted lines indicating the position of the parts when the switch is in use. Fig. 2 is an end elevation
35 of the switch mechanism, showing the carrier-wheel in edge view and the main track in section, the parts being in a position for using the branch track. Fig. 3 is a sectional plan view, part of the framework and the operating-levers being removed and some of the frame members showing in transverse section, two positions of the movable switch-rail sections being shown, as in Fig. 1. Fig. 4 is a side elevation looking toward the main track
40 from the side opposite the switch. Fig. 1^a is a perspective view showing the main line in condition for use. Fig. 1^b is a similar view showing the switch in use and the main-line section removed. Fig. 2^a is a view similar to
45 that shown in Fig. 2, except that the positions
50

of the movable parts are reversed in the full and dotted lines from the corresponding positions shown in said Fig. 2.

In the drawings there is shown a suspending-bracket, which in top or plan view is substantially triangular in form, the outlines of which are indicated in Fig. 1, and the vertical members (marked 5 6 7) are shown in transverse section in Fig. 3. This frame is intended to be secured by its top plate 8 to a fixed support above the track, and its depending members 5, 6, and 7 are adapted to fixedly support the rails adjacent to this switch, the brackets 5 and 7 supporting the main-track rails 9 and 10, respectively, and the bracket 6 supporting the branch rail 11.

12 represents a rocking crank or eccentric shaft, the journals 13 of which have bearings, respectively, in the lower ends of the members 6 and 7, the outline of the member 7 being clearly shown in Fig. 2. This crank-shaft has integrally formed therewith in the preferred construction the arms 14, which are parallel to each other and carry at their extremities the integrally-formed main-track-
75 rail section 15, which has its axis in line with the journals of the crank-shaft.

The casting of the parts 12, 14, and 15 together is feasible, economical, and therefore preferred. Of course they may be separately formed and adequately secured together. These parts constitute a swinging frame carrying one of the track-rail sections, which is rocked about the frame axis. The track-section 15 is of such length as to bridge the gap between the main-track rails 9 and 10 and is supported by feet or flanges 16, depending from the brackets 5 and 7.

17 represents pitmen, which are journaled on the eccentric or crank portion of the shaft 12 and carry at their outer extremities the curved switch-track section 18. The pitmen 17 are preferably journaled upon the rock-shaft 12 by the simple straps 19. The end of the curved switch-rail, which is adapted to make junction with the main-track rail 10, has a sliding support on the support 16, formed with the bracket 7, while the opposite end of said curved switch-rail section has a sliding bearing on a support 20, formed as a part of 100

the leg 6. The supports 16 and 20 have depressed portions 16^a and 20^a at their rear ends to permit the rail 18 to move down as its axis raises and lowers.

5 The means for rocking the crank-shaft and thereby moving the switch-rails will be best understood from Figs. 1 and 2. The operating-lever (marked 21) has one end secured to a rock-shaft 22, journaled in bearings in the top 10 plate 8. A hook-lever 23 has one end thereof secured to the rock-shaft 22 and projects over the switch-track, its extremity being provided with a hook 24, adapted to engage and support the main-track section 15 when the 15 latter is not in use. In some instances it may be found necessary to weight the hooked lever, and I have shown such a weight in Figs. 1^a, 1^b, and 2^a, and marked the same 23^a. A link 25 pivotally connects the hook-lever 23 with 20 one of the arms 14, as clearly shown in Fig. 3, the pivots being marked 26 27.

28 represents the carrier-wheel, and 29 its frame. This carrier is shown in Fig. 1 on the main-track rail 9.

25 The operation of the parts is as follows: Assuming the main-track section to be in place, as shown in Fig. 1, carriers may pass freely beneath the operating-arm 21 toward the point of the switch. After the carrier has 30 passed the switch, if it be desired to run it back upon the branch track, the operating-lever 21 will be pulled down from the position shown by the dotted lines in Fig. 2 to the position shown by the full lines in said figure. 35 The result of this movement is to turn the rock-shaft 22, which will thereby raise the outer end of the hook-lever and pull upwardly on the link 25, which, being connected to the arm 14, will cause the crank-shaft 12 to rock 40 on its bearing, thus carrying the straight switch-section over into the position shown by the full lines in Fig. 2, the arc of its movement being indicated by the dotted line of said figure. During this movement the arms 45 14 will be carried back, thus throwing the pivot 27 to the rear of the crank-shaft, the crank of the latter being projected forwardly and acting through the pitman 17 to thrust the movable section 18 from the position 50 shown by the full lines in Fig. 3 to the position shown by the dotted line in said figure.

It will be observed that the arms 14 are slightly curved between their ends, and the arrangement of the pivots is such that the 55 parts are locked at the end of their movement in operative position. When the curved switch-section is in place, the lever 21 lies in position to intercept the frame 29, as shown in Figs. 1 and 2.

60 Obviously, instead of employing a supporting-frame serving as a hanger for the rails and bearings for the crank-shaft journals and supports for the movable sections, the ends of the rails may be supported by hangers or 65 otherwise and the journals of the crank-shaft have bearings upon separate castings carried by the rails. I prefer, however, to provide

the depending frame to support the ends of the track-rails and to afford journal-bearings for the crank-shaft, because all of the parts 70 may thus be kept in accurate alinement.

It will be understood that my invention is not limited to the arrangement shown. The straight switch-section may be connected by the pitmen to the crank or eccentric and the 75 curved section rigidly connected to the crank. Obviously, also, the construction of the frame and the arrangement of the parts will be modified to the various situations of a straight switch instead of a back switch, as here 80 shown.

Without limiting my invention, therefore, to these precise details of construction and arrangement of parts, I claim—

1. A switch of the class described, comprising in combination with a main track having a gap therein, a branch track and movable rail-sections adapted to bridge the gaps and a crank or eccentric shaft to which one of said movable rails is rigidly and the other pivotally secured whereby when the shaft is rocked one of said sections is moved out of and the other into operative position, substantially as described.

2. A switch of the class described, comprising in combination a main track and a branch and movable rail-sections adapted to bridge the gaps in the main track and between the main track and the branch, a rocking crank or eccentric shaft, one of said movable 100 rail-sections being rigidly connected to the crank-shaft and having its axis in line with the journals thereof and the other being pivotally connected to the eccentric or cranked portion of the shaft whereby when the shaft 105 is rocked one of said sections is reciprocated and the other is swung, substantially as described.

3. In a switch of the class described, the combination with a main track and a branch, 110 of a frame adapted to support the ends of the track-rail at the switch, a crank-shaft journaled in said frame a movable rail-section rigidly secured to the crank-shaft and a movable rail-section pivotally connected to the 115 cranked portion of said shaft, substantially as described.

4. In a switch of the class described, the combination with the main track and branch rails, of a hanger for supporting the ends of 120 said rails, a crank-shaft journaled in said hanger, a movable rail-section rigidly connected with said crank-shaft, a sliding rail-section pivotally connected with the eccentric portion of said shaft and supports upon said 125 hanger for said movable rail-sections, substantially as described.

5. The combination with the main and branch tracks, of a hanger for supporting the 130 ends of said tracks, a crank-shaft journaled on the hanger, a rail-section rigidly connected with the crank-shaft and a second rail-section pivotally connected with the eccentric portion thereof, an operating-lever and a link piv-

totally connecting said operating-lever and the crank-shaft whereby the latter may be rocked in its bearings to shift one of said rails into and the other out of position, substantially as described.

5 6. The combination with the main-track and branch-track rails, of a pivoted frame carrying a rail-section and a second rail-section connected to said frame eccentrically to its axis and means for rocking said frame whereby one of said rails is caused to swing therewith and the other is caused to reciprocate, substantially as described.

10 7. The combination with the main track and branch, of a pivoted frame carrying a track-rail section, a rail-section eccentrically connected with said frame and adapted to be moved into and out of position by the swing-

15 ing thereof, an operating-lever having a hooked extension to support the swinging rail 20 and a link connecting said lever with the frame, substantially as described.

8. The combination with the main and branch tracks and a swinging frame carrying a track-rail section, of a movable track-rail 25 section pivotally connected to said frame eccentrically to its axis and an operating-lever connected with said frame and said lever being adapted when operated to project across the track into the path of a carrier, substan- 30 tially as and for the purpose described.
